UNITED STATES PATENT OFFICE.

GEORGE D. HOFFMAN, OF CHICAGO, ILLINOIS, ASSIGNOR TO NORWALL MANUFACTURING COMPANY, OF CHICAGO, ILLINOIS.

AIR-VALVE FOR RADIATORS.

1,083,933.

Specification of Letters Patent. Patented Jan. 13, 1914.

Application filed March 31, 1911. Serial No. 618,075.

To all whom it may concern:

Be it known that I, GEORGE D. HOFFMAN, a citizen of the United States, residing at Chicago, county of Cook, State of Illinois, have invented a certain new and useful Improvement in Air-Valves for Radiators, and declare the following to be a full, clear, and exact description of the same, such as will enable others skilled in the art to which it 10 pertains to make and use the same, reference being had to the accompanying drawings, which form a part of this specification.

A common form of heating system employs an air line which communicates with 15 each radiator in the system through a suitable automatic valve; the purpose of the air line being to carry from the radiators to a discharge point the foul air and such water as may leak through the valves. The air in 20 passing through the automatic valves, and the steam which enters the valve, both contain more or less dirt and grit which collects upon the valve seats and interferes with the successful operation of the valve. When 25 the valves become dirty it is necessary to clean them in order to bring them back to normal working conditions; but, as such valves have heretofore been constructed, it has required the services of a skilled me- 30 chanic to open the valves to clean and then to readjust them properly, because the advantages gained through cleaning by an unskilled person might be more than offset by the disadvantage following from improper 35 adjustment.

It is one of the objects of my invention to produce an air valve of the type to which I have referred which may be cleaned when necessary, without requiring the services of 40 a skilled mechanic and without danger of disarrangement of the adjustment of the parts.

A further object of my invention is to produce an air valve which shall be simple 45 in construction, efficient in operation, and, to a degree, automatically adjustable.

The various features of novelty whereby my invention is characterized will herein- 50 after be pointed out with particularity in the claim; but, for a full understanding of my invention and of its objects and advantages, reference may be had to the following detailed description taken in connection with the accompanying drawing, wherein:

55 Figure 1 is a side elevation of a radiator

having my improved valve device applied thereto; Fig. 2 is a vertical section on a larger scale through the valve device detached from the radiator; and Fig. 3 is a side elevation of a portion of the valve, the coupling being unscrewed and the plug carrying the valve seat detached.

Referring to the drawing: 1 represents a radiator, 2 an air valve as a whole, and 3 an air pipe leading from the valve.

The valve comprises a casing 4 having a suitable nipple 5 for attachment to a radiator. In the cover of the casing is a screw plug 6 which may be adjusted in the vertical direction. At the bottom of the casing 70 is a downwardly projecting sleeve 7 which lies directly below the screw plug and forms the outlet from the casing.

8 is an expandible member flexibly suspended from the lower end of the plug, preferably by means of a ball and socket joint 75 9. In the arrangement shown the member 8 comprises a cup-shaped shell with its mouth directed downward and a thin diaphragm 10 extending across the mouth of 80 the shell and having its edges secured to the shell so as to seal the same hermetically. In the course of manufacture, a few drops of alcohol are placed within the shell and sufficient heat is applied to vaporize the alcohol 85 and drive out the air through a small opening left for that purpose. The opening is then closed while the shell remains hot and, when the shell cools, a partial vacuum is produced therein and the diaphragm is 90 flexed inwardly.

At the center of the diaphragm is secured an elongated valve 11 which projects down into the sleeve 7. A pipe 12, with its upper end capped, fits within the lower end of the 95 sleeve, and is provided with a valve seat 13 at the upper end of a port 14 extending through the cap. The upper end of the pipe 12 preferably lies considerably above the valve seat and the cap is countersunk 100 as indicated at 15 in order to provide a guide for the valve. The depending part of the pipe is internally screw-threaded, as at 16, for the purpose of receiving the screw-threaded end of the pipe 3. The pipe 12 is 105 provided with an annular flange 17 which abuts against the end of the member 7 and aids in making a tight joint between this member and the pipe. I prefer to make the lower end of the member 7 conical in shape 110

and to countersink the upper surface of the flange 17 correspondingly. The pipe 12 is held in place by means of a coupling 18 which is screw-threaded upon the sleeve 7 5 and has an internal annular flange 19 which engages with the underside of the flange 17.

After the parts have been assembled as shown in Fig. 2, the screw plug is adjusted until the valve is just clear of its seat when 10 the parts are cold, thus permitting air to flow out of or be drawn out from the radiator to which the valve may be attached until steam enters the valve. The plug may then be soldered in place so that its adjustment 15 cannot accidentally be altered. When the valve is to be applied in a heating system, the coupling 18 is unscrewed and the pipe 12 drops out of the valve. The pipe 12 is then screwed upon the upper end of the 20 air pipe, as indicated in Fig. 1, the nipple is screwed into the radiator, and the coupling is then screwed upon the sleeve 7, drawing the end of the pipe 12 into the sleeve, and securing the valve device and the air 25 pipe firmly together.

In operation, air is drawn from the radiator through the air line until steam enters the valve device, whereupon the expandible member forces the valve against its seat and 30 closes the outlet so that the steam cannot escape from the radiator. When grit or dirt collects upon the valve seat and prevents the valve from closing tightly, it is only necessary to unscrew the coupling 18 and to bend 35 the pipe 3 from the position shown in full lines in Fig. 1 to the position shown in dotted lines, disengaging the pipe 12 from the valve and exposing it so that the grit and dirt can readily be removed. After the 40 valve seat has been cleaned the pipe is restored to the position indicated in full lines in Fig. 1, bringing the upper end of the pipe 12 into the sleeve 7, and the coupling is slipped up and screwed upon the sleeve 45 until the flange 17 is seated firmly against the lower end of the sleeve. Consequently the cleaning operation requires no change in the adjustment of the parts except the simple lifting out of the pipe 12 which, when

put in place again, can only assume its 50 proper normal position, being centered by the sleeve and having its inward movement limited and determined by the engagement of the flange with the end of the sleeve. It is impossible for the valve proper to become 55 disarranged because it hangs free and, as soon as the pipe is inserted in the sleeve the valve enters the concave guiding surface in the upper end thereof and is directed toward its seat even though the casing should be in such a position that the valve does not hang truly vertical.

It will thus be seen that I have provided a simple and novel valve device in which the valve seat may be kept clean by anyone 60 having enough skill to unscrew a simple coupling without possibility of leaving the valve poorly adjusted after the cleaning has been effected.

While I have illustrated and described 65 only a single preferred form of my invention, I do not desire to be limited to the particular structural details thus illustrated and described; but intend to cover all forms and arrangements which fall within the terms 70 employed in the definitions of my invention constituting the appended claim.

I claim:

In combination, an air valve device comprising a casing having a hollow hub or 75 sleeve projecting downwardly from the bottom thereof, an expandible member mounted in said casing, a discharge pipe having a part projecting into and fitting in said hollow hub and a flange engaging with the end 80 of the hub, means for clamping said flange against the hub, the part of the pipe lying within the hub having a port therethrough, and a valve on said expandible member extending into proximity to said port to control the same.

In testimony whereof, I sign this specification in the presence of two witnesses.

GEORGE D. HOFFMAN.
